UNITED STATES PATENT OFFICE.

MARLEY FOTHERINGHAM HAY, OF GLASGOW, SCOTLAND.

HOUSING FOR THE CONNING-TOWERS, PERISCOPES, AND VENTILATING-SHAFTS OF SUBMARINES.

1,099,126.

Specification of Letters Patent.

Patented June 2, 1914.

Application filed February 20, 1914. Serial No. 819,994.

To all whom it may concern:

Be it known that I, MARLEY FOTHERINGHAM HAY, a subject of the King of Great Britain and Ireland, and a resident of Glasgow, Scotland, have invented certain new and useful Improvements in Housings for the Conning-Towers, Periscopes, and Ventilating-Shafts of Submarines, of which the following is the specification.

10 This invention has for its object to provide improved housings for the conning tower and the periscopes of submarines, and if desired also for the ventilating shafts of such vessels, so as to materially reduce the resistance produced by these projecting parts when the vessel is running submerged. Thus in view of this decreased resistance the speed of the vessel submerged for any given power is increased, and the radius of action submerged for any given speed is considerably enhanced.

It has always been a general practice in submarines to fit a conning tower for purposes of observation and navigation when running on the surface in rough weather.

25 This conning tower is usually circular in section, or some other form which is productive of a large amount of resistance to propulsion when the vessel is submerged. With a view 30 to somewhat decreasing this resistance it has likewise been a general practice to fit a housing forming a wave breaker or "fairwater" around this conning tower giving it a more or less ship shape form. This fairwater, 35 however, has been made lower than the conning tower itself, and the top of the conning tower which is provided with port holes for purposes of observation has projected above the top of the fairwater. This projecting

40 top is in itself, however, productive of a very large amount of resistance. To overcome or materially decrease this resistance according to the first part of the invention there is provided an improved form of wave breaker in which the after portion is carried up to a height corresponding with the height of the conning tower. By this means the resistance of the projecting portion of the conning tower is reduced to a minimum. This 45 after portion of the housing is covered over and forms a usual navigating platform when running on the surface in fair weather.

The usual two periscopes pass up through the housing, and according to the second 50 part of the invention a considerable portion

of the parts of these periscopes which extend above the housing are inclosed in a single additional housing tapered to a vertical edge at both ends and extending up from the navigating platform as high as may be convenient or possible. "Dead water" is thus prevented from forming behind the rounded after side of each periscope, and consequently the resistance these parts formerly produced is materially reduced.

55 The space in both housings between the periscopes can be utilized as a convenient lead for the ventilating shafts, and where such shafts are fitted with the improved system of valves, forming the subject-matter 60 of a concurrent application for a patent, so that they do not require to be pulled down preparatory to diving, they are also so inclosed by the housings that the resistance they would otherwise offer is obviated. Consequently as the ventilating shafts do not require to be pulled down preparatory to diving, the time required to prepare the vessel for diving is thereby materially reduced.

65 The improved housings are shown on two 70 accompanying sheets of explanatory drawings, Figure 1 being an end elevation, Fig. 2 a side elevation, and Fig. 3 a plan thereof.

75 As shown in the drawings, the conning tower A is surrounded by a housing B forming a wave breaker or fairwater. This housing is on its forward side carried up from the vessel's superstructure C as formerly, only to a level which is below the level 80 of the sidelights on the side of the conning tower, to allow a direct line of vision being obtained ahead through the sidelights; but according to the invention the after portion of the housing B is made to extend up to the full height of the conning tower A, and it 85 is tapered and ends in a fine vertical edge. Thus the resistance offered by the conning tower A when the vessel is under way submerged is reduced to a minimum.

90 The usual two periscopes D, E also project up through the after portion of the housing B the top of which is covered over and forms a navigating platform, and an additional single housing G, tapered to a vertical edge at both ends and extending up from the navigating platform as high as may be possible or convenient, so incloses a considerable portion of the upwardly extending parts of these periscopes that the resistance 95 formerly offered by them when the vessel is 100 running on the surface in fair weather. The 105 usual two periscopes pass up through the housing, and according to the second part of the invention a considerable portion of the upwardly extending parts of these periscopes that the resistance formerly offered by them when the vessel is 110

under way submerged is reduced to a minimum. Further, two ventilating shafts H, J, each fitted with the improved system of valves hereinbefore referred to, so that they do not require to be pulled down previous to diving, are so led that they extend up through both housings B, G and, as they are therefore similarly sheathed or inclosed by the housings so that dead water is also prevented from forming behind their rounded after sides, they offer little or no resistance to the propulsion of the vessel submerged, and consequently there is no objection to their being left in position and not drawn down preparatory to diving. The usual apertures are also provided in both housings to permit of the entry and exit of water and air to their interiors when

diving so that these structures do not require to be made pressure resisting.

20

What I claim is:—

A housing for the conning tower of usual height forward but extending aft the full height of the tower and tapering aft to a fine edge; on this housing a second housing 25 tapered to vertical edges at both ends, and inclosing upwardly extending portions of periscopes and ventilating shafts.

In testimony whereof I have signed my name to this specification, in the presence of 30 two subscribing witnesses.

MARLEY FOTHERINGHAM HAY.
